UNITED STATES PATENT OFFICE.

MERVIN V. ARNOLD, OF EVANSVILLE, INDIANA.

COMPRESSOR.

Application filed December 11, 1922, Serial No. 606,123. Renewed October 27, 1924.

To all whom it may concern:

Be it known that I, MERVIN V. ARNOLD, a citizen of the United States, residing at Evansville, in the county of Vanderburgh and the State of Indiana, have invented certain new and useful Improvements in Compressors, of which the following is a full, clear, and exact description, such as will enable any one skilled in the art to make and use the same.

My invention relates to refrigerating machines, particularly machines designed for the use of small consumers, as for example, in households, but it is distinctly understood that the novel features herein described are by no means limited to that type or size of machines. The chief object of my invention is to provide a machine which is more efficient and which produces a greater refrigerating effect with a lower cost of construction and at a less expenditure of power for operation than those now in use.

A further object is to provide a more simple, compact device and yet which will still be effective in its operation to accomplish the purposes desired.

A third object of my invention is to provide an efficient arrangement of parts which can be economically constructed and not easily get out of repair, but which can be readily operated.

A fourth object is to provide a refrigerating machine which will be portable and self contained and which may be if desired removed from one location to another.

A fifth object is to provide an efficient type of cooling means more especially in connection with a nonfreezable and substantially nonevaporating fluid to cool the flooded condensing chamber of the machine, and thus allow continual use of the same cooling fluid.

A sixth object is to provide a refrigerating machine with a compressor to circulate the refrigerant by drawing the same into the crank case under vacuum and through ports into the cylinder where it is compressed and discharged into the cooled condensing chamber.

A seventh object is to provide an efficient power transmission by means of a walking beam which transforms the power and applies the same through an up and down movement of a connecting rod to the compressor piston, thus minimizing lateral pressure on the cylinder walls.

An eighth object is to provide a nonleakable substitute for the old time stuffing box by use of a bellows attached to the compressor crank case and to the walking beam member over the fulcrum point.

A ninth object is to provide a quick, exact and easy adjustment of the clearance between piston and cylinder head by means of an adjustable bracket member that supports the main driving gear which operates the power end of the walking beam.

A tenth object is to provide an effective, noiseless and durable exhaust valve at the top of the cylinder head which requires neither springs nor cages, nor grinding, nor adjustment.

An eleventh object is to provide an automatic expansion valve so located that it requires no care or attention and no equalizing pipes to equalize the different specific gravities of the refrigerant in vapor and liquid forms, said expansion valve being provided to regulate the supply of refrigerant to the expansion coils as required by the changes of temperature effecting the same.

The further objects of my invention and the method of carrying out the objects hereinbefore stated, will be fully set out in the drawings, specifications and claims. In general, the machine operates on the usual principle; that is, a liquefied gas or sufficiently volatile liquid is allowed to expand through a fine orifice into a closed expansion coil—and is vaporized and thereby reduced to a low temperature, absorbing the necessary heat from the chamber by which it is surrounded. From this coil the gas is exhausted into a partial vacuum in the base of a compressor passing thence through parts into the compressor cylinder by which it is compressed. The compressed gas or vapor necessarily at a high temperature, is then passed into a cooling chamber where the heat is absorbed by a cooling coil therein and the gas condensed to a liquid. From this chamber the liquid passes through the orifice and again starts on its cycle of operation.

I accomplish this refrigerating cycle by operation of the mechanism illustrated in the attached drawings and hereinafter more fully described.

The drawings which are for illustrative purposes only, show a small machine adapted to be set on a household refrigerator with

the connection from the machine to the interior of the refrigerator.

In these drawings:

Fig. 1, is a front elevation of the machine shown in place on the top of an ordinary household refrigerator, a portion of which refrigerator is broken away to show the expansion chamber or coil therein.

Fig. 2, is an enlarged view of the expansion valve and the float mechanism controlling the same.

Fig. 3, is a sectional elevation taken through the center of the compressor cylinder and the cooling chamber on the line 15 III-III of Figs. 6 and 7.

Figs. 4 and 5 are respectively a plan view and enlarged section on the line V-V showing more clearly the detail of the exhaust valve for the head of the compressor cylinder.

Fig. 6, is an end or side elevation of the machine showing more specifically the relation of the radiator and cooling fan and the pipe connections of the condenser coil to 25 the radiator.

Fig. 7, is a plan view of the radiator and operating motor, with the compressor shown in section on the line VII-VII of Fig. 3.

Fig. 8, is a perspective view of a freezing 30 tray adapted for use within an ordinary family refrigerator.

Fig. 9, is a diagrammatic view showing the cycle of operation and also showing diagrammatically the various mechanisms involved, with approximate pressures and temperatures.

Fig. 10, is a side view of one form of expansion coil adapted for use in connection with my machine.

Referring now to the drawings in which the various parts are indicated by the same numerals in all the views,

1, is an ordinary household refrigerator having the front partially broken away to 45 show the refrigerating expansion coil 2 therein. 3, represents a metal base which supports and secures together the entire mechanism, while 4 is a felt pad under the base 3 which absorbs vibration of the moving parts when operating in a fixed position. 50 5 represents bolts or screws which secure the base and supported parts to the object on which the same is placed.

Formed on the base member 3 are lugs 6 which secure and support the power motor, 55 7. On one end of the drive shaft 8 of the motor 7 is fastened a noiseless rawhide or bakelite and linen pinion 9 which is inserted through an opening 10 in the side of the transmission case housing 11. Above the 60 said opening 10 is secured a split cover plate 12 which closes about the drive shaft and prevents oil and grease from escaping from the transmission case through the opening 65 10. A hole 13 in the housing 11, relieves the

oil pressure. The transmission case housing 11 is secured to the base 3 by bolts 14 and to the air tight compressor base 15 and 16. This compressor base 15 is also secured to the base 3 by bolts 17.

Mounted on the base 3 inside the transmission case is a bracket 18 with a recessed flange set over a projection 19 formed on the said base 3 and held by bolts 20. By loosening these bolts this bracket may be 75 moved away from or toward the compressor base and the walking beam 27 be varied in effective length to regulate the clearance of the piston 42 in the cylinder 39. Fastened through the bracket 18 is a stud bolt 80 21 carrying a bushing 22 which forms a bearing on which rotates a gear 23 which meshes with the pinion 9.

Eccentrically located in the gear 23, to serve as a cam member is a fixed stud 24 with a bushing 25 which slides in a slot or fork 26 formed in one end of a walking beam 27. The opposite end 28 of the walking beam 27 extends through an opening 29 into the compressor base 15. The two ends 27 and 28 of 90 this walking beam being secured together by bolts 30. A bellows member 31 with heads 32, and 33 is fastened to the compressor base by bolts 34 and to the walking beam by bolts 30. The walking beam is journaled on a fulcrum 35 which in turn is supported by brackets 36 extending from the compressor base 15. The compressor base is kept in true alignment with the gear bracket 18 by a recessed slot 37 in the bottom of the base 100 which fits over a projection 38 on the base 3 and is in alignment with the projection 19.

Mounted on the compressor base 15 is the compressor cylinder 39 secured in place by bolts 40. In the walls of this cylinder are 105 ports 41 forming passages from the base to the cylinder. Inside the cylinder is a piston 42 with piston rings 43 and an oil groove 44. A pin 45 inside the piston journals the connecting rod 46, the opposite end of which 110 rod is journaled on a pin 47 carried by the walking beam 28.

Secured to the top of the cylinder 39 is a head 48 secured by bolts 50. 49 is a port hole through this head. A spring flap valve 115 51 covers port 49 and is held in place by a cover plate 52, both being secured in place by bolts 50.

Formed as a part of the compressor base 15 but separated by a partition wall is 120 a liquid storage chamber 53. Mounted above the compressor base 15 is a dome shaped jacket 54 which encloses the cylinder 39 and storage chamber 53 and is held in place by bolts 55. A purge valve 56 enters this pressure chamber 54 at the top and is covered by a cap 57. Inside the pressure chamber 54 is a pipe coil 58 which enters and leaves through the walls of same. This coil is connected by fittings and short pipes 125 130

59, 59^a to a storage radiator 60 which contains a nonfreezable cooling fluid. This radiator is held on the base 3 by bolts 61 which secure supporting brackets 62.

6 A fan shaft 63 is journaled in a bracket 64 fastened to the base. This shaft carries a fan 65 and is rotated by means of the pulley 66, a belt 67 from the pulley 68 on the motor shaft 8 furnishing the operating 10 means.

11 A guard 69 encloses the fan. In the liquid storage chamber 53 there is located an expansion valve assembly comprising parts as follows: 70 is a circular plate secured over a pipe opening 71 in the bottom of the storage chamber 53 and having a tapering or needle valve seat 72 formed therein through which the liquid refrigerant passes. Mounted on the plate 70 are brackets 73 which support 15 a circular top plate 74 corresponding in size to the plate 70 and carrying two bearing lugs 75. A hole 76 is located in the center of the top plate 74 in direct alignment with the valve seat 72, through which hole 76, 20 a valve stem 77, having a tapering valve corresponding to the valve seat 72, is slidably operated to close and open the valve 72. This valve stem 77 is raised and lowered by means of a lever arm 78 to which it is secured by a loose pin bearing. The end of the lever 78 nearest to the valve stem 77 is loosely journaled on a pin 77^a carried by the bearing lugs 75, and a ball float 79 is attached to the opposite end thereof and floats 25 on the liquid in the storage chamber. A stop lug 80 limits the movement of the arm 78 and prevents the valve stem 77 from being entirely disengaged from the valve opening 72. A screen 81 of fine mesh surrounds the space between members 70 and 74 30 to filter the liquid gas passing into expansion valve 72.

35 Connected to the liquid storage chamber 53 and directly under the valve 72 is one end of an expansion pipe coil 82 which enters and is shown enclosed by the ice chamber 1^a of the domestic refrigerator. The said pipe 82 enters the top of the ice chamber 1^a and is coiled therein downward 40 as far as may be desired.

45 The opposite end of the coil leaves the top of the chamber and enters the compressor base at the point 84. 83 are union fittings for coupling the coils after insertion 50 through holes 85 in the ice box. 86^a is a charging in valve on the vacuum side of the coil pipe line. Valves 86 may be located 55 between these fittings and the expansion valve and compressor base to retain the refrigerant in the machine before the expansion coils 82 are connected to the same. The pipe 82 is preferably coiled to form shelves 60 on which may be inserted trays 89 with removable subdivisions 90, which trays are 65 for the purpose of freezing any substance

placed therein while the machine is running. Current is brought in from a suitable source on wires 91 through fuses 92 having the required resistance to the switch 93 and from this switch wires 94 connect with the 70 motor 7. 95 is a pilot lamp wired in the circuits to indicate when the machine is in operation. This system of wiring may be used with either an automatic control feature or semi-automatically by the use of a 75 switch to turn on or off the current.

80 In the operation of the device, the motor shaft 8 rotates the pinion 9 which engages the larger gear 23 and thereby reduces the speed of the device. The end 27 of the walking beam is oscillated upward and downward by means of the pin 24 on the said gear 23. This motion is transmitted through the opposite end 28 of the walking beam and the connecting rod 46, to the piston 42. Being operated over a fulcrum point this motion through the leverage obtained thereby reduces the power required to operate the device. A bellows member 31 85 incloses the fulcrum bearing and retains 90 the refrigerant in the compressor base 15 and prevents the lubricant from entering same from the transmission case. This bellows arrangement replaces the old time stuffing box and thus reduces the power required to operate a shaft in a tight stuffing box and absolutely eliminates leakage and eventual loss of the refrigerating gas.

95 It is obvious that some changes or modifications may be made in the device within the scope defined by the appended claims without departing from the true intent and meaning of the invention.

100 Having now fully described my invention, what I claim as new and desire to secure by Letters Patent is:—

105 1. In a compressor, a walking beam having a longitudinal slot formed in one end and a pin in the opposite end thereof, a fulcrum for said beam, a cylinder mounted 110 over the pin end of the said beam, a piston in said cylinder, a connecting rod from the said walking beam pin to the said piston, a crank pin engaging the slotted end of the said beam, means for driving said pin 115 of the said beam, means for shifting the said crank pin longitudinally to vary the stroke and clearance in the said cylinder.

120 2. In a compressor, a pinion driving means therefor, a gear meshing with said pinion, a compressor base, brackets extending from the said compressor base, a fulcrum pin carried by the said brackets, a walking beam fulcrumed on the said pin, a longitudinal slot formed in one end of 125 the said beam, an eccentrically located pin projecting from one side of the said gear into the slot in the said walking beam, a cylinder mounted on the said compressor base, a piston in the said cylinder and a 130

connecting rod from the said walking beam to the said piston.

3. In a compressor, a pinion, driving means therefor, a gear below the said pinion meshing therewith, means for supporting and adjusting the said gear longitudinally with relation to said pinion and longitudinally with relation to a walking beam, a compressor base, a fulcrum pin, means for supporting said pin, a longitudinally disposed walking beam fulcrumed on the said pin, a longitudinal slot formed in one end of the said beam, an eccentrically located pin projecting from one side of the said gear into the slot in the said walking beam, a cylinder mounted on the said compressor base, a piston in the said cylinder and a connecting rod from the said walking beam to the said piston.
4. In a compressor, a power transmission housing, a pinion and gear meshing enclosed in the said housing, a compressor base, brackets extending from the said compressor base, a fulcrum pin carried by the said brackets, a walking beam fulcrumed on the said pin, a longitudinal slot formed in one end of the said beam, an eccentrically located pin projecting from one side of the said gear into the slot in the said walking beam, a cylinder mounted on the said compressor base, a piston in the said cylinder, a connecting rod from the said walking beam to the said piston, and means for driving said pinion.
5. In a compressor, the combination with a base plate, of a compressor base mounted on the said base plate and a transmission housing, a longitudinally adjustable bracket mounted on the said plate, a bearing pin rigidly attached to and extending outward from the said bracket, a gear rotatably mounted on the said bearing pin, a motor on the said base plate, a pinion on the rotor shaft of the said motor meshing with the top of the said gear, a bracket extending laterally from the said compressor base, a pin mounted in the said bracket, a walking beam fulcrumed on the said pin, one end of the said walking beam having a longitudinal slot formed therein, a pin carried by the opposite end of the said walking beam, an eccentrically disposed pin extending from one face of the said gear into and engaging with the slot in the said walking beam, a compressor cylinder mounted on the top of the said compressor base, a piston in the said cylinder, a bearing pin in the said piston, a connecting rod from said piston pin to the said walking beam pin.
6. In a compressor, a walking beam having a longitudinal slot formed in one end and a pin in the opposite end thereof, a fulcrum for said beam, a bellows enclosing said fulcrum, a cylinder mounted over the pin end of the said beam, a piston in said

cylinder, a connecting rod from the said walking beam pin to the said piston, a crank pin engaging the slotted end of the said beam, means for driving said pin and means for shifting the said crank pin longitudinally to vary the stroke and clearance in the said cylinder.

7. In a compressor, a pinion driving means therefor, a gear meshing therewith, a compressor base, brackets extending from the said compressor base, a fulcrum pin carried by the said brackets, a bellows enclosing the said brackets and fulcrum pin, a walking beam fulcrumed on the said pin, a longitudinal slot formed in one end of the said beam, an eccentrically located pin projecting from one side of the said gear into the slot in the said walking beam, a cylinder mounted on the said compressor base, a piston in the said cylinder and a connecting rod from the said walking beam to the said piston.

8. In a compressor, a pinion, driving means therefor, a gear below the said pinion meshing therewith, means for supporting and adjusting the said gear longitudinally with relation to said pinion and longitudinally with relation to a walking beam, a compressor base, a fulcrum pin, means for supporting and enclosing said pin, a longitudinally disposed walking beam fulcrumed on the said pin, a longitudinal slot formed in one end of the said beam, an eccentrically located pin projecting from one side of the said gear into the slot in the said walking beam, a cylinder mounted on the said compressor base, a piston in the said cylinder and a connecting rod from the said walking beam to the said piston.

9. In a compressor, a power transmission housing, a pinion and gear meshing, enclosed in the said housing, a compressor base, brackets extending from the said compressor base, a fulcrum pin carried by the said brackets, a bellows sleeve enclosing said brackets and fulcrum pin, a walking beam fulcrumed on the said pin, a longitudinal slot formed in one end of the said beam, an eccentrically located pin projecting from one side of the said gear into the slot in the said walking beam, a cylinder mounted on the said compressor base, a piston in the said cylinder, a connecting rod from the said walking beam to the said piston, and means for driving said pinion.

10. In a compressor the combination with a base plate having longitudinal aligning means thereon, of a compressor base mounted on the said base plate and held in alignment by said aligning means, means attaching the said transmission housing to the said base, a bracket adjustably mounted on the said base plate, and held in alignment by the said aligning means, a bearing pin rigidly attached to and extending outward from

the said bracket, a gear rotably mounted on the said bearing pin, means for rotating the said gear, a fulcrum carried by the said compressor base, a walking beam fulcrumed thereon, one end of the said walking beam having a longitudinal slot formed therein, an eccentrically disposed pin extending from the face of the said gear into and engaging with the slot in the said walking beam, a compressor cylinder mounted on the top of the said compressor base, a piston in the said cylinder, and means connecting the said piston and the said walking beam.

11. In a compressor the combination with a base plate having longitudinal aligning means thereon, of a compressor base mounted on the said base plate and held in alignment by said aligning means, means attaching the said transmission housing to the said base, a bracket adjustably mounted on the said base plate, and held in alignment by the said aligning means, a bearing pin rigidly attached to and extending outward from the said bracket, a gear rotatably mounted on the said bearing pin, means for rotating the said gear, a fulcrum carried by the said compressor base, a walking beam fulcrumed thereon, one end of the said walking beam having a longitudinal slot formed therein, an eccentrically disposed pin extending from the face of the said gear into and engaging with the slot in the said walking beam, a compressor cylinder mounted on the top of the said compressor base, a piston in the said cylinder, and means connecting the said piston and the said walking beam.

12. In a compressor, the combination with a base plate having longitudinal aligning means thereon, of a compressor base mounted on the said base plate and held in alignment by said aligning means, means attaching the said transmission housing to the said base, a bracket adjustably mounted on the said base plate, and held in alignment by the said aligning means, driving means rotatably mounted in the said bracket, a fulcrum carried by the said compressor base, a walking beam fulcrumed thereon, one end of the said walking beam having a longitudinal slot formed therein, an ec-

centrically disposed pin extending from the face of the said driving means into and engaging with the slot in the said walking beam, a compressor cylinder mounted on the top of the said compressor base, a piston in the said cylinder, and means connecting the said piston and the said walking beam.

13. In a compressor, the combination with a base plate having longitudinal aligning means thereon, of a compressor base mounted on the said base plate and held in alignment by the said aligning means, means attaching the said transmission housing to the said base, a bearing adjustably mounted on the said base plate, and held in alignment by the said aligning means, a gear rotably mounted on the said bracket, means for rotating the said gear, a fulcrum carried by the said compressor base, a walking beam fulcrumed thereon, one end of the said walking beam having a longitudinal slot formed therein, an eccentrically disposed pin extending from the face of the said gear into and engaging with the slot in the said walking beam, a compressor cylinder mounted on the top of the said compressor base, a piston in the said cylinder, and means connecting the said piston and the said walking beam.

14. In a compressor for vaporous gases, an enclosed base, a compressor cylinder mounted thereon, a piston mounted therein, a walking beam, means connecting said beam and said piston, means operating said walking beam, a fulcrum for said beam, and a bellows acting as a closure for said base attached to said base and to said walking beam near said fulcrum, a vapor inlet into said base, passages in the cylinder walls leading from the said base to the said cylinder whereby vapor must pass through the said base and be subjected to the heat thereof before passing into the said cylinder, and an exhaust port leading from the said cylinder.

In testimony whereof I have hereunto set my name.

MERVIN V. ARNOLD.
